UNITED STATES PATENT OFFICE.

ALBERT G. ELVIN, OF SOMERVILLE, NEW JERSEY.

DOOR-OPERATING MECHANISM.

1,073,894.

Specification of Letters Patent. Patented Sept. 23, 1913.

Application filed July 24, 1912. Serial No. 711,255.

To all whom it may concern:

Be it known that I, ALBERT G. ELVIN, of Somerville, in the county of Somerset and State of New Jersey, have invented a 5 certain new and useful Improvement in Door-Operating Mechanism, of which improvement the following is a specification.

My invention relates to pneumatically actuated means for effecting the opening 10 and closure of doors, more particularly the fire doors of steam boiler and other furnaces, and its object is to provide an automatically operating mechanism of such general class or type, by which a door may be 15 automatically opened and closed, at desired intervals, these operations continuing, without attention or manipulation by an operator, during the entire period that motive fluid is permitted to be supplied to the apparatus.

The improvement claimed is hereinafter fully set forth.

In the accompanying drawings: Figure 1 is a front view, in elevation, of a firebox 25 door operating mechanism, illustrating an embodiment of my invention, in position on the back head of a locomotive firebox; Fig. 2, an end view of the same with the firebox in section; Fig. 3, a vertical longitudinal central section, on an enlarged scale, through the door motor; Fig. 4, a similar section through the valve motor; and, Fig. 5, a vertical transverse section through the valve motor, on the line *a* *a* 30 of Fig. 4.

My invention is herein exemplified as applied in connection with a fire door appliance comprehending two reciprocating members, 9, 9^a, performing the function of 40 fire door leaves or sections, which are fitted to slide horizontally toward and from each other in guides, 3, on a door frame, and to cover and uncover, as the case may be, a firing opening, 4, in a firebox or furnace, 45 5, to which the door frame is connected. The door section reciprocating members are moved from and toward each other, to open and close, respectively, the firing opening, by means of levers, 12, 12^a, pivoted by pins 50 or bolts, 13, to a gear casing hereinafter described, the lower and longer arms of said levers being coupled to the door sections. Intermeshing segment gears, 17, 17^a, are formed on the levers, concentric with 55 their pivots, 13, and by the oscillation of

said segment gears about their axes, the door sections will be moved from or toward each other, as the case may be. A hand lever, 18, is pivoted to the bottom guides of the door frame, and is provided with a 60 longitudinal slot, 18^a, engaging a pin, 18^b, fixed to the door section, 9, for the purpose of operating the door sections manually, when desired.

The application of my invention in connection with a door mechanism comprising two movable door sections, involves, in operative combination with such mechanism, the following principal characteristic members or elements, viz: a fluid pressure 65 "door motor", by which the door sections are alternately moved from and toward each other, to effect the opening and closure of the firing opening, said motor, as an entirety, being indicated on the drawings by 70 the reference symbol, A; an automatically operating fluid pressure "valve motor", by which the supply and exhaust of motive fluid to and from the "door motor" are effected and controlled, said "valve motor", 75 80 as an entirety, being indicated on the drawings, by the reference symbol, B; and a manually operated "regulating valve", by which the speed of the "valve motor", and consequent number of operations of the door 85 sections within any determined period, is regulated and controlled by the operator, or the operation of the door sections is intermittent for any desired period, in accordance with the conditions governing the 90 supply of fuel to the firebox. The regulating valve, as an entirety, is indicated on the drawings by the reference symbol, C.

The door motor, A, herein exemplified, is not, in and of itself, claimed as of my 95 present invention, and a motor of different specific structure may, if desired, be substituted therefor, in the discretion of the constructor, as a member of a complete door operating mechanism embodying my invention. It will not therefore be fully and in complete detail set forth, but its operative principle and relation to the coöperating elements of the complete mechanism will be herein described sufficiently to enable them 100 to be understood.

In the instance shown, a fluid pressure cylinder, 25, is bolted to the top of the door frame, and is closed at one of its ends, in this case the left hand end, by a head, 26. 110

The cylinder, 25, is formed integral with, or fixed to, an open bottomed gear casing, 25^a, into which the segment gears, 17, 17^a, project, and through which it is connected to the door frame. The end of the cylinder opposite that to which the head, 26, is secured, is closed by a head, 26^a. A piston, 28, is fitted in the cylinder, 25, and is formed integral with, or fixed to, a piston rod, 28^a, which is made of such diameter as to cause the area of the piston effective for pressure to be substantially less on the piston rod side than on the opposite side, the former being, say, one half the latter, thus constituting the piston a differential one. The bore of the cylinder, 25, at, and for some distance from its end which is farther from the piston, is in correspondence with the diameter of the piston rod, which is coupled, 20 by a pin, 19^a, to an arm, 19, on the segment gear, 17, the pin passing through a longitudinal slot in the arm, so as to admit of the vibration of the latter about the axis of the segment gear. Movement to the right or to 25 the left, as desired, is imparted to the piston by fluid pressure, as hereinafter described, and it will be seen that such movement will, through the segment gears and their constructions, move the door sections apart, or bring them together, as the case may be.

The supply and exhaust of motive fluid to and from the opposite sides of the piston, 28, to effect the opening and closing movements of the door sections, are effected 30 by the following means. A supply pipe, 31, controlled by a throttle or shut off valve, 32, leads from any suitable source of fluid pressure supply, as, for example, the main reservoir of an air brake system, to a valve 35 chamber, 34, in the casing of the valve motor, B, and thence into the larger bore of the cylinder, 25, on the left hand side of the piston, being connected to the head, 26. Communication, through said pipe, between 40 the valve chamber and the cylinder, is controlled by a door opening supply valve, 33, which is normally held seated by a spring, 33^a. A branch pipe, 31^a, which is not valve controlled or obstructed, leads from the supply pipe, 31, above the supply valve, 33, into a longitudinal passage, 43, in the cylinder, 25, from which passage another passage, 43^a, leads into the smaller bore of the cylinder, adjacent to the right hand end thereof. 45 Communication between the passages, 43 and 43^a, is controlled by a door closing supply valve, 53, which is fixed on a vertical stem, 55, and is normally held seated by a spring, 53^a.

60 A shoe, 28^b, is fitted on the upper side of the piston rod, 28^a, in position to abut against the lower end of the stem, 55, of the door closing supply valve, 53, said shoe being recessed at and adjacent to its end 65 nearer the valve stem, and upwardly in-

clined from its recessed portion, which is not in contact with the valve stem, to its portion of full thickness. When, in the traverse of the piston rod to the right, the inclined portion of the shoe strikes the valve 70 stem, it thereby unseats the valve, 53, and holds it unseated during the remainder of the traverse of the piston and rod to the right, and when, in the traverse of the piston rod to the left, the recessed portion of the shoe comes below the valve stem, the latter is thereby freed from contact with the shoe, and the valve, 53, is seated by the pressure above it and by its spring, 53^b. The construction of valve and shoe above described accords, in all substantial particulars, with that set forth in Letters Patent No. 1,030,063, granted and issued to me under date of June 18, 1912, and is not therefore claimed as of my present invention. 75

In the traverse of the piston, 28, to the left, during which the door sections are closed, motive fluid is exhausted from the left hand end of the cylinder, 25, through the supply pipe, 31, the valve chamber, 34, (below the valve 33), and an exhaust port, 48, in said chamber, the area of which may be adjusted as desired by a regulating valve, 51, so as to cushion the exhaust and prevent the slamming of the door sections in closing. 95

In order to prevent the door sections from slamming open, the right hand end head, 26^a, of the cylinder, 25, is provided with a spring cushion, against which the piston rod, 28^a, abuts, when nearing the end of its right hand stroke, said spring cushion comprising a plunger, 26^b, fitted in the head and in a cylindrical extension, 26^c, thereof, and a helical spring, 26^d, abutting at one end on the plunger and at the other on a plug or head, 26^e, secured adjustably in the outer end of the extension, 26^c, of the cylinder head. 100

The valve motor, B, which is herein exemplified, is desirably applicable in the practice of my invention, in the particulars of simplicity, compactness, and economy in construction, and the absence of stuffing boxes and other packed joints, but any other suitable and preferred form of motor which is adapted to effect the intermittent opening movements of the door opening supply valve, 33, may be substituted, if desired, in the discretion of the constructor. The motor shown in the drawings, which is of 105 the double cylinder direct acting type, is of the following construction, and while, for the purpose of avoiding dead centers, it is provided with duplicate sets of motor elements, it will be obvious that, if desired, it 110 may be constructed with one set only.

Two motor cylinders, 60, located side by side and as closely together as possible, are cast integral with, and on one side of, a casing, 61, of substantially rectangular 115

transverse section, the side of which farther from the cylinders constitutes the bed plate or base of the motor. The cylinders, 60, are closed at their ends by removable heads, 60^a, and each of them is fitted with a piston, 62, in which opposite longitudinal slots, 62^a, are formed, through which slots a crank shaft, 63, passes freely. Pairs of transverse pins, 62^b, which are flattened on their 5 adjacent sides, are fitted in the pistons, 62, between the slots, 62^a, each pair being adapted to engage the crank pin of a double crank, 63^a, on the crank shaft which passes through said slots. The crank shafts, 63, 10 which, through such connection, are rotated directly by the pistons, are mounted in upper bearings, 64^b, in the valve casing hereinafter described, and lower bearings, 61^a, in the casing, 61, and they are also supported, 15 on roller bearings, 61^b, in the casing, 61. The side of the casing, 61, nearer the cylinders, is finished truly, and a valve casing, 64, is suitably secured to it. The valve casing is bored out parallel with, and in the 20 axial planes of, the cylinders, to form two valve chests, in each of which a distribution valve, 65, of the inside admission piston type, is fitted to reciprocate, and said chests are closed, at their ends, by removable heads, 25 64^a. A longitudinal slot, 65^a, through which the adjacent crank shaft, 63, passes freely, is formed in each of the distribution valves, and each of said valves is also centrally recessed, opposite said slot, to engage an actuating cam, 63^b, fixed on the crank shaft.

A supply pipe, 66, leads from any suitable source of fluid pressure supply, which is preferably the steam space of the boiler, to a supply port, 66^a, which opens into each 30 of the valve chests, at the middle thereof, and induction ports, 68, lead from the middle portions of the valve chests to the opposite ends of the adjoining cylinders. Exhaust ports, 69, lead from the induction 35 ports, near their outer ends, to the corresponding ends of the valve chests, and supplemental exhaust ports, 69^a, are formed in the heads, 64^a, of the valve chests, said ports communicating, one with the other by a longitudinal port, 70, in the valve casing, and one of the ports, 69^a, communicating with an exhaust pipe, 71, through which, by the reciprocation of the distribution valves, motive fluid is exhausted, in proper relation 50 to the movements of the pistons, from the ends of the valve chests.

Coincident rotation of the two crank shafts, 63, is effected and insured by intermeshing spur gears, 72, fixed thereon, and 55 the crank, 63^a, of one of the shafts is set at right angles to that of the other, thereby preventing dead centers and enabling the motor to be started regardless of the positions of the pistons. A worm, 73, fixed on one of the crank shafts, 63, engages a worm

wheel, 74, fixed on a shaft, 75, journaled in a bearing, 75^a, in the casing, 61, and the shaft, 75, carries a lifting cam, 76, which actuates a lifting rod, 77, working in a guide in the casing, by the reciprocation of which, in the rotation of the shaft, 75, the door opening supply valve, 33, is unseated, at desired intervals, to operate the door motor.

The valve motor above described is not claimed as of my present invention, but is fully set forth in Letters Patent of the United States No. 1,050,528, granted and issued to me under date of January 14, 1913.

The supply pipe, 66, of the valve motor, is governed, preliminarily, by a throttle or shut off valve, 67, between which and the valve motor there is interposed the regulating valve mechanism, C, by which the speed of the valve motor, and, consequently, of the door motor, may be increased or diminished, or the operation of the door motor may be discontinued from time to time, as may be required by the conditions of service. The regulating valve mechanism does not, in and of itself, constitute part of my invention, and any suitable appliance, many of which are familiar to those skilled in the art, may be used, in the discretion of the constructor. As shown in the drawings, a regulating valve of ordinary construction is mounted in a casing, 78, and actuated by a handle, 79, by the engagement of which with holes or notches in a fixed quadrant, 80, the desired control of the flow of motive fluid through the supply pipe, 66, is effected.

In the operation of my invention, the throttle valves, 67, and 32, of the valve motor and door motor, having been opened and the regulating valve mechanism adjusted to cause the door motor to be operated at the speed desired, the door sections will be automatically opened and closed continuously throughout the period during which the operator allows motive fluid to be admitted to the valve motor, the intervals between the movements of the door sections being governed by the speed of the motor, as determined by the adjustment of the valve regulating mechanism. As the piston of the door motor moves toward the right, upon the admission of motive fluid to its left hand side, by the unseating of the door opening supply valve, and thereby imparts opening movement to the door sections, the door closing supply valve is unseated by the piston rod shoe, and motive fluid is admitted to the smaller bore of the door motor cylinder. Such admission of fluid will not, however, prevent the door sections from being fully opened, by reason of the preponderance of pressure on the larger area of the left hand side of the piston, but will serve to cushion the movement of the piston and prevent the slamming open of the doors, which cushion-

ing action is supplemented by that of the spring cushion device in the right hand head of the cylinder. As soon as the lifting cam of the valve motor clears the lifting rod, the 5 door opening supply valve is automatically seated and the motive fluid on the left hand side of the piston of the door motor is exhausted, the rate of the exhaust being governed by the adjustment of the exhaust 10 regulating valve. The pressure in the smaller bore of the door motor cylinder then moves the piston to the left and closes the connected door sections, slamming being prevented by the regulation of the exhaust. 15 When the piston has moved nearly to the end of its traverse in this direction, the door closing supply valve is freed from the pressure of the piston rod shoe and automatically seated, and the closing movement is 20 completed by the expansion of the motive fluid in the smaller bore of the door motor cylinder and the momentum of the door sections. The alternate opening and closing operations above described similarly continue 25 so long as motive fluid is allowed to be admitted to the door motor.

It will be understood that in referring to the door sections as being "automatically" opened and closed by means of the operation 30 of the valve motor, it is meant that such operation and its result are continuously conducted and effected, in proper sequence, during the entire period that motive fluid is supplied to the valve motor, as above described, without any manipulation whatever 35 by an operator, in contradistinction to a succession of intermittent operations, each of which requires, and is dependent upon, the manual adjustment of a valve controlling 40 the supply and exhaust of motive fluid to and from the motor.

By means of the separate valve operating motor which is independent of the door motor, the length of the time interval between 45 the successive movements of the door may be adjusted to suit different conditions by simply shifting the regulating device to give the desired speed to the valve motor, and this is an important feature in the practice 50 of my improvement, since, as the fuel recedes in the bin of the tender, the fireman must necessarily take a longer interval of time between the delivery of successive shovelfuls of fuel through the fire door 55 opening. Various other conditions may also arise under which it is desirable to adjust the time interval between the opening movements of the door, which may be readily accomplished by setting the regulating device 60 as above described.

I claim as my invention and desire to secure by Letters Patent:

1. In a door operating mechanism, the combination of a door, a door motor coupled thereto, and an independent valve motor au-

tomatically and alternately controlling the admission and exhaust, respectively, of motive fluid to and from the door motor.

2. In a door operating mechanism, the combination of a door, a door motor coupled thereto, an independent valve motor automatically and alternately controlling the admission and exhaust, respectively, of motive fluid to and from the door motor, and a regulating mechanism controlling the rate of speed of the valve motor.

3. In a door operating mechanism, the combination of a door, a door motor coupled thereto, a door opening supply valve controlling the admission and exhaust of motive fluid to and from the door motor, an independent valve motor, and means, actuated by said valve motor, for automatically and alternately opening and closing said door opening supply valve.

4. In a door operating mechanism, the combination of a door, a door motor coupled thereto, a door opening supply valve controlling the admission and exhaust of motive fluid to and from the door motor, an independent valve motor, means, actuated by said valve motor, for automatically and alternately opening and closing said door opening supply valve, and a regulating mechanism controlling the rate of speed of the valve motor.

5. In a door operating mechanism, the combination of a door, a door motor coupled thereto, a door opening supply valve controlling the admission of motive fluid to the door motor in one direction of movement and permitting the exhaust thereof in the opposite direction, a valve motor, means, actuated by said valve motor, for automatically and alternately opening and closing said door opening supply valve, a door closing supply valve controlling the admission of motive fluid to the door motor for movement in the opposite direction to that effected by the opening of the supply valve, and means, actuated by the door motor, for opening said door closing supply valve.

6. In a door operating mechanism, the combination of a door, a door motor coupled thereto, a door opening supply valve controlling the admission of motive fluid to the door motor in one direction of movement and permitting the exhaust thereof in the opposite direction, a valve motor, means, actuated by said valve motor, for automatically and alternately opening and closing said door opening supply valve, a door closing supply valve controlling the admission of motive fluid to the door motor for movement in the opposite direction to that effected by the opening of the supply valve, means, actuated by the door motor, for opening said door closing supply valve, an exhaust regulating device for cushioning the movement of the door in one direction, and

a spring resistance device for cushioning the movement of the door in the opposite direction.

7. In a door operating mechanism, the combination of a door, a fluid pressure actuated reciprocating door motor coupled thereto, an automatically seating door opening supply valve controlling the admission of motive fluid to the door motor in one direction of movement and permitting the exhaust thereof in the opposite direction, a fluid pressure actuated valve motor, means operated by said motor, for intermittently opening said supply valve, an automatically seating door closing supply valve controlling the admission of motive fluid to the door motor for movement in the opposite direction to that effected by the opening of the supply valve, means, actuated by the door motor, for opening said door closing supply valve, and a manually actuated regulating mechanism controlling the valve motor.

8. In a door operating mechanism, the combination of a door, a fluid pressure actuated mechanism coupled to and imparting movement in opposite directions to said door, and a separate fluid pressure actuated mechanism automatically controlling the movements of said door moving mechanism.

9. In a door operating mechanism, the combination of a door, a fluid pressure actu-

ated mechanism coupled to and imparting movement in opposite directions to said door, a separate fluid pressure actuated mechanism automatically controlling the movements of said door moving mechanism, and manually actuated means for regulating said controlling mechanism.

10. In a door operating mechanism, the combination of a door, a fluid pressure actuated mechanism coupled to and imparting movement in opposite directions to said door, a separate fluid pressure actuated mechanism automatically controlling the movements of said door moving mechanism, and means for cushioning the movements of said door moving mechanism at their opposite terminals.

11. In a door operating mechanism, the combination of a door, a fluid pressure motor coupled thereto, a supply valve controlling the admission of fluid to said door motor, mechanism operating independently of the door motor to automatically open and close said valve periodically, and manually actuated means for adjusting the time interval between the successive movements of said valve.

ALBERT G. ELVIN.
